UNITED STATES PATENT OFFICE.

HENRY C. FLEMING AND WILLIAM F. ROYSTER, OF DENISON, TEXAS.

FLOOR-JACK.

No. 849,059.

Specification of Letters Patent.

Patented April 2, 1907.

Application filed August 9, 1905. Serial No. 273,409.

To all whom it may concern:

Be it known that we, HENRY C. FLEMING and WILLIAM F. ROYSTER, citizens of the United States, residing at Denison, in the 5 county of Grayson, State of Texas, have invented certain new and useful Improvements in Floor-Jacks; and we do hereby declare the following to be a full, clear, and exact description of the invention, such as will enable others skilled in the art to which it 10 pertains to make and use the same.

This invention relates to floor-tongs.

One object of the invention is to provide an exceedingly simple, inexpensive, durable, 15 and efficient carpenters' tongs for the laying of ceiling, flooring, and wall-boards.

Another object of the invention resides in the provision of a pair of tongs adapted to embrace the studding, joist, or sleepers and 20 provided with means for pushing the board tightly in place before it is nailed.

With these and other objects in view the present invention consists in the combination and arrangement of parts, as will be 25 hereinafter more fully described, shown in the accompanying drawings, and more particularly pointed out in the appended claims, it being understood that changes in the form, proportion, size, and minor details may be 30 made within the scope of the claim without departing from the spirit or sacrificing any of the advantages of the present invention.

In the drawings, Figure 1 is a side elevation of the invention. Fig. 2 is a top plan view. Fig. 3 is a detail view. Fig. 4 is a 35 section on line 4 4 of Fig. 2. Fig. 5 is a detail view of one of the dogs. Fig. 6 is a side elevation showing the tool in use.

Referring now more particularly to the accompanying drawings, the reference character 40 1 designates a lever provided at one end with a handle 2, with its opposite end bent outwardly to form a jaw 3. Secured to the lever 1 intermediate its ends is a metallic or 45 other strap 4, between which and the lever 1 is a second lever 5, there being a bolt 6 piercing the strap or band 4 to prevent disengagement of the lever 5 therefrom. It will be observed that this lever 5 is not provided 50 with a handle member and that its end adjacent the jaw 3 of the lever 1 is bent outwardly to form a jaw 7 for coöperation with the jaw 3.

In the outer end of each jaw 3 and 7 we provide 55 an opening in which we fit the screw-threaded shank 9 of each of the studding,

joist, or sleeper engaging dogs 10 and 11, the said dogs being fitted against the inner faces of the respective jaws 3 and 7. If these dogs 10 and 11 were mounted tightly with respect 60 to the jaws 3 and 7, there would be a tendency of the dogs sliding with the sliding movement of the lever 1 regardless of the fact that each dog is provided with a sharp engaging point 12. It is for this purpose 65 that we formed the said openings in the jaws a little larger than the diameter of the shanks 9, so that the dogs will have a little play with respect to the jaw, so that when the lever 1 is moved in either direction for the moving of 70 the jaws the dogs will not be disturbed, but will engage tightly the studding, joist, or sleeper. However, the dogs 10 and 11 cannot 75 become disengaged from the respective jaws 3 and 7, for the reason that we provide a nut 13 for engagement with the screw-threads of the shanks 9, as shown. While this movement of the dogs longitudinally of the jaws is permitted, we secure suitable stops 14 and 15 at one end of each dog for engagement with the corresponding edge of the 80 back of each of the respective jaws, preventing rotation of the dogs.

It will be observed that the lever 1 is preferably straight in the rear of the aforesaid strap 4, while the lever 5 is bent upon a compound curve, as shown. In order to force the respective dogs 10 and 11 of the jaws 3 and 7 toward each other, we provide alining perforations 14 and 15 in the respective levers 90 for the slidable reception of a bolt 16, upon which bolt there is mounted a helical spring 17 for engagement with the inner faces of the respective levers to force the dogs toward each other, as well understood. By 95 means of a suitable pivot-bolt 18, passed through the lever 1, we mount a bar 19 for swinging movement. The outer end of this bar is provided with teeth 20 for firm engagement with the top of the studding, joist, or 100 sleeper to brace the tongs when forcing a board into place. It will be observed that this brace-bar 19 is pivotally connected to the lever 1 only—that is, it is not connected in any way to the lever 5. This brace-bar 19 105 is twisted intermediate its ends, so that the teeth 20 may lie transversely of the studding, joist, or sleeper.

Experiments have shown that if a pull be exerted upon both levers 1 and 5 there is a 110 tendency of the dogs loosening in their grip upon the studding, joist, or sleeper. For

this reason the lever 5 is not provided with a hand-grasp, as is the lever 1, and pull is exerted only upon the lever 1 by grasping the handle portion 2 of the latter. By pulling 5 solely upon the lever 1 the dogs, as well as the brace-bar 19, engage more firmly the joist, studding, or sleeper. It is for the reasons just stated that the brace-bar 19 is secured to the lever 1 and not to the lever 5 or 10 both of the levers.

What is claimed is—

A device of the class described, comprising levers pivoted intermediate their ends, each

lever having a jaw portion, a dog loosely mounted in each jaw portion, a spring arranged between the levers to force said dogs normally toward each other, and a brace-bar pivotally connected to one of the levers. 15

In testimony whereof we affix our signatures in presence of two witnesses.

HENRY C. FLEMING.
WILLIAM F. ROYSTER.
